UNITED STATES PATENT OFFICE.

ALBERT PHILIPP, OF STANTON, NEBRASKA.

BEET-HARVESTER.

SPECIFICATION forming part of Letters Patent No. 663,834, dated December 11, 1900.

Application filed January 26, 1898. Renewed May 5, 1900. Serial No. 15,645. (No model.)

To all whom it may concern:

Be it known that I, ALBERT PHILIPP, of Stanton, in the county of Stanton and State of Nebraska, have invented certain new and useful Improvements in Beet-Harvesters; and I hereby declare that the following is a full, clear, and exact description thereof, reference being had to the accompanying drawings, which form part of this specification.

10 This invention relates to machines for harvesting sugar-beets, chicory, and other succulent roots and which first cut off the projecting tops of the beets and subsequently remove the body of the same from the ground.

15 The invention is an improvement upon my Patent No. 552,444, granted to me on December 31, 1895.

The principal objects of the present invention are to provide the machine with an automatically-adjustable roller and knife, which latter will cut the beets according to their height without wasting them and to prevent the roller and adjustable cutter from crushing or ruining the beets in rolling thereover, 25 which is accomplished by imparting a positive rotary motion to the said roller.

Another improvement consists in the means for substantially lifting the adjustable self-adjusting roller and knives and the diggers 30 from the ground when the machine is to be transported or turned.

The invention therefore consists in the novel construction and combination of parts hereinafter described and claimed, and illustrated in the accompanying drawings, in which

Figure 1 is a perspective view of the complete machine. Fig. 2 is a top plan view thereof. Fig. 3 is a transverse section on line 40 33, Fig. 1. Fig. 4 is a detail side elevation.

The main frame of the machine consists of the parallel side bars A A, connected by transverse end pieces a and an intermediate piece a', to which the seat A⁵ is attached. The frame 45 is supported upon rear axle B, upon which are wheels b b', a sprocket-wheel b² being fixed on the axle of the wheel b', between the wheel and the frame, for a purpose hereinafter explained. The front end of the frame is supported 50 on a curved axle B², provided with wheels B³, and a tongue a³ is made fast to this axle and pivoted to a clip a² on the front bar a.

To the front end of the frame, in rear of wheels B³, is secured a topping-cutter C and a sweep C' which are attached to the frame 55 by means of bar C² or in any other suitable manner, the cutter C being adapted to cut off the tops of the beets, as indicated in the drawings, and the sweep C' to direct these tops to one side of the machine out of the way. 60

In rear of sweep C' is a roller D, mounted on a shaft d, which extends through slots e in the sides E² of a vertically-movable frame, which is suitably guided on the bars A. The guides may be provided with friction-rollers 65 e' to facilitate the rise and fall of the frame E. The side pieces E² are connected by transverse pieces E', as shown, so that they move together. The shaft d may be held down in the slots by means of set-screws d², having 70 their brackets d' attached to the side E².

On the projecting ends of shaft d are mounted loose wheels D², which practically carry the weight of the roller D and allow the same to be revolved with or on shaft d by 75 means of a sprocket D⁵, driven by a chain b³ from the sprocket b² on wheel b'.

Just in rear of and below roller D is a horizontal knife or trimmer D⁴, which is attached at one end to one of the side pieces of frame 80 E. The roller D is preferably provided with a shallow spiral rib D' on its periphery, by which any material resting upon knife D⁴ is worked off and discharged at one end of the roller. A brush E⁴ is attached to the frame 85 E in rear of roller D in position to clear the surface from dirt that would otherwise adhere thereto.

In rear of frame E is a transverse shaft F, journaled in bars A, and on this shaft are 90 fixed arms F', which are pivotally connected to the end pieces of frame E, so that by rocking the shaft frame E, with roller D and knife D⁴, can be raised or lowered. Shaft F can be rocked by a lever F', which is provided 95 with an ordinary hand-latch F³, adapted to engage a toothed segment F² on one of the bars A, as shown.

In rear of roller D is a diagonally-arranged sweep G, which is suspended on vertically-movable bars g, and one end of the sweep is connected by a link g' to an arm f on shaft F, and the bar g on the rear end of sweep G is connected to the upper end of an angle-

lever H, pivoted to the adjoining bar A, the lower end of this lever being connected to a rod I, the forward end of which is connected to the depending lower end of lever F', so 5 that when said lever is rocked to elevate the frame E the sweep G will be also elevated.

On the lower edge of sweep G is a rubber strip G', which will yield if it strikes an unyielding object or the upper end of a beet 10 without crushing the latter or injuring the shield.

In rear of sweep G are the diggers J, which are attached to the lower ends of bars J', respectively pivoted on the side bars A. The 15 right-hand bar J' is connected to rod I, which extends rearwardly thereto, and the left-hand bar J' is connected by rod I' to an arm i on shaft F, as shown. Therefore when shaft F is rocked, so as to lift frame E and sweep G, 20 the diggers J are swung above the surface of the ground, so that the machine can be readily transported or turned.

The machine is driven along and over a row of beets. The knife C first comes in contact 25 with the beets and tops them, as indicated in the drawings, these tops being of no use to the factory in making sugar. The severed tops are moved off to one side by the sweep C'. As many of the beets will still project 30 above the ground more than is necessary, the trimming-knife D⁴ is used, which removes superfluous top portions of overgrown beets. In order to prevent this knife D⁴ trimming 35 too much off the beets, the roller D is employed, and as it first rolls over the beet it lifts the trimming-knife, so that it cuts off no more than is necessary. This lifting of the trimmer is regulated by means of the set-screws D², and when the shaft of roller D 40 strikes against these set-screws the frame E, with the trimmer-knife, is raised over the beets, and thus automatically adjusted to regulate the cut of the beets. As stated, the 45 first knife C clips the stems and a part of the beet, if very high, as indicated in the drawings. Then if the roller D comes in contact with any projecting beet it rides thereover, lifting the knife D⁴ with it, thus preventing 50 the latter cutting the beets wastefully, and 55 the beet is thus cut only according to its height, which is the most important feature in the machine and I believe peculiar to the present invention. The rubber shield on the lower edge of the sweep G prevents the latter injuring the projecting beets when passing 60 thereover and at the same time insures that all the cuttings from knife D⁴ will be swept to one side of the machine. The diggers J then loosen the beets and the rods J³ 65 on the diggers lift the prepared beets high enough to clear them from the soil and let them drop on the top of the ground ready for loading.

When the machine is not in operation, the 65 lifters, sweep G, and frame E can all be raised above the ground, so as not to interfere with the free movement of the main frame.

Having thus described my invention, what I therefore claim as new, and desire to secure by Letters Patent thereon, is—

1. In a beet-harvester, the combination with the topping-knife, and sweep; of a roller in rear of said knife and a trimming-knife controlled by said roller, for the purpose and substantially as described. 70

2. In a beet-harvester, the combination of the vertically-movable frame, the adjustable roller mounted therein and the knife attached to said frame and movable therewith, substantially as and for the purpose described. 75

3. In a beet-harvester, the combination of the vertically-movable frame, the adjustable roller mounted therein, the knife attached to said frame and movable therewith, and means for regulating the play of the roller on the 85 frame, substantially as described.

4. In a beet-harvester, the combination of the vertically-movable frame, the roller journaled in said frame, the trimming-knife attached to said frame, and the sweep in rear of 90 said roller, and means for raising said sweep and roller and frame, for the purpose and substantially as described.

5. In a beet-harvester, the combination of the main frame and the vertically-movable frame 95 thereon, the roller journaled in said movable frame having a spiral rib on its periphery, the trimming-knife below the roller attached to said movable frame, the sweep in rear of said roller, and means for raising said sweep 100 and roller and frame, for the purpose and substantially as described.

6. In a beet-harvester, the combination of the main frame, the roller, the roller carrying wheels loosely mounted on the roller-shaft, and means for rotating said roller independently of its wheels, substantially as and for the purpose set forth. 105

7. The combination of a vertically-movable frame, a roller journaled therein, the roller carrying wheels loosely mounted on the roller-shaft, and means for rotating said roller; with the trimming-knife attached to said frame, all substantially as and for the purpose described. 110

8. In a beet-harvester, the combination of the vertically-movable roller, the trimming-knife beside and movable with the roller, and controlled thereby, the sweep in rear of said roller and the diggers in rear of the 120 sweep, substantially as and for the purpose described. 115

9. In a beet-harvester, the combination of the vertically-movable roller, the trimming-knife beside and movable therewith and controlled by the roller, the sweep in rear of said roller and the diggers in rear of the sweep, with means for simultaneously elevating the roller and knife, the sweep and the diggers, for the purpose and substantially as described. 125

10. In a beet-harvester, the combination of the topping-knife and its sweep, the adjustable roller in rear thereof, the trimming-knife beside and adjustable with and by the roller 130

and the sweep in rear of said roller provided with a yielding or rubber strip on its lower edge, for the purpose and substantially as described.

5 11. In a beet-harvester, the combination of the topping-knife and its sweep, the adjustable roller in rear thereof, the trimming-knife beside and adjustable with and by the roller and the sweep in rear of said roller; with the

10 diggers in rear of the latter sweep, mounted upon pivoted bars; and means for elevating said roller sweep and the diggers, substantially as and for the purpose described.

12. In a beet-harvester, the combination of the topping-knife and its sweep, the adjustable roller in rear thereof, the trimming-knife beside and adjustable with and by the roller and the sweep in rear of said roller; with the

15 diggers in rear of the latter sweep, mounted upon pivoted bars, the vertically-movable frame carrying said roller and trimming-knife, a rock-shaft and connections substantially as described for elevating said frame, and means operated from said rock-shaft for

20 elevating said sweep and the diggers, substantially as and for the purpose described.

13. In a beet-harvester, the combination of the front topping-knife and its sweep, the vertically-movable frame in rear of said topping-

25 knife, the roller journaled in said frame, a knife attached to said frame and movable therewith; the sweep in rear of said roller, the pivoted bars in rear of said sweep, the

30 diggers attached to said bars and means for driving said roller from the main wheels;

with the rock-shaft, connections between said rock-shaft and vertically-movable frame for elevating the latter, levers and rods for lifting said sweep, and the rods and connections for elevating the diggers all operated 40 from said rock-shaft, substantially as described.

14. In a beet-harvester, the combination of the main frame, the front topping-knife and its sweep, the vertically-movable frame in 45 rear of said topping-knife, the shaft journaled therein, the roller and wheels on said shaft, a knife attached to said frame and movable therewith, and a brush on said frame for cleaning said roller; a sweep in rear of said 50 roller, the pivoted bars in rear of said sweep and the diggers attached to said bars; with the main wheel, a sprocket driven by one of the main wheels and a sprocket-chain and sprocket for driving said roller from said 55 main wheel; a rock-shaft on the main frame, connections between said rock-shaft and vertically-movable frame for elevating the latter, the levers and rods, for lifting said sweep, and the rods and connections for elevating 60 the diggers, all operated from said rock-shaft, substantially as described.

In testimony that I claim the foregoing as my own I affix my signature in presence of two witnesses.

ALBERT PHILIPP.
